UNITED STATES PATENT OFFICE.

WILLIAM GRIFFIN, OF FAIR HAVEN, NEW YORK, ASSIGNOR OF ONE-HALF
TO FRANK M. JONES, OF SAME PLACE.

POTATO-DIGGING MACHINE.

SPECIFICATION forming part of Letters Patent No. 393,007, dated November 20, 1888.

Application filed May 5, 1888. Serial No. 272,987. (No model.)

To all whom it may concern:

Be it known that I, WILLIAM GRIFFIN, a citizen of the United States, residing at Fair Haven, in the county of Cayuga and State of New York, have invented certain new and useful Improvements in Potato-Diggers, of which the following is a specification.

This invention relates to certain new and useful improvements in potato-diggers of that class in which plows are provided for turning up the hill, and in which provision is made for the elevation of the plows and diggers in transportation from place to place.

The object of the invention is to improve upon previous constructions of this character, to provide a strong and durable machine, and one that will be efficient in operation.

The novelty resides in the peculiar combinations and the construction, arrangement, and adaptation of parts, all as more fully hereinafter described, shown in the drawings, and then particularly pointed out in the appended claims.

The invention is clearly illustrated in the accompanying drawings, which, with the letters of reference marked thereon, form a part of this specification, and in which—

Figure 1 is a side elevation of a potato-digger constructed in accordance with my invention. Fig. 2 is a top plan of the same.

Referring now to the details of the drawings by letter, A designates the axle, and B B the main wheels. The axle is journaled in T's on the ends of the longitudinal bars b, which are secured to the front transverse bar, a. Secured to the bar a, and extending backward, are the bars C C, connected at their rear ends by a cross-bar, c, and the two cross-bars a and c are joined by the longitudinal bar D, parallel with the bars b, and preferably substantially midway of the same. These parts are preferably formed of suitable gas-pipe, and the several parts connected together by suitable couplings and T's, as shown.

To the longitudinal bar D are secured the teeth or diggers E E, and to the rear cross-bar, c, are also preferably secured two or more teeth of the same construction. Rising from the rear cross-bar, c, and from the bars b near their front ends, are the standards d, forming

a support for the upper frame, F, which is preferably formed of gas-pipe, and suitably braced by means of cross-bars, and the parts connected by suitable couplings. The rear ends of the side bars of this upper frame are extended to form handles e e. Suitably held in a holder, f, supported by the central bar, D, is the plow G, preferably provided with a mold-board, as shown.

From the front cross-bar of the upper frame extends forward the bar h, the forward end of which is connected to an extension of the bar D by a vertical rod or bar, g, to the rear face of which is secured a semicircular strip provided upon its rear side with a plurality of notches, i, to receive the ring of the draft-pole H.

To the central cross-bar, j, of the upper frame is pivoted a rod, I, one end of which extends rearward and forms an operating-lever, 7c and the other end inclines forward and upward, as shown.

On the axle is pivoted the upright frame, consisting of the two bars suitably connected together, and the two bars formed on their front faces with a plurality of notches, l, for a purpose hereinafter specified. The upper cross-bar of this upright frame slides loosely over the upwardly-extended end of the rod I.

Rising from the forward cross-bar of the upper frame are the standards m, connected by a cross-bar, n, adapted to engage the notches of the side bars of the upright frame.

L is a spring connected at one end with the bar h and at its other end to the upwardly-extending portion of the rod I.

When it is desired to transport the machine from one place to another, or it is desired for any reason to elevate the diggers and plow from the ground, it is only necessary to manipulate the lever I, when the cross-bar n will engage the notches of the upright frame and hold it in its adjusted position. The spring L serves to hold the said parts at all times in engagement.

What I claim as new is—

1. In a potato-digger, the combination, with the axle and the upper and lower frames connected together and pivoted on the axle, of the upright frame provided with notches, means

for elevating said frame to engage said notches, and the spring L, all arranged and operating substantially as described.

2. In a potato-digger, the combination, with 5 the axle and the upper and lower frames connected together and pivoted on the axle, of the upright frame pivoted on the axle and provided upon its front face with notches, as described, the elevated cross-bar on the upper 10 frame engaging said notches, and means for raising the frame, substantially as shown and described, and for the purpose specified.

3. The potato-digger described, consisting of the axle, the wheels, the lower frame, the

diggers and plow carried thereby, the upper 15 frame connected to the lower frame, and all pivoted on the axle, the lever I, pivoted to the central cross-bar of the upper frame, the upright frame provided with the notches, as described, the cross-bar n on the upper frame, 20 adapted to engage said notches, and the spring L, all arranged and operating substantially as described.

WILLIAM GRIFFIN.
